[57] CLAIM

The ornamental design for a furniture arm frame or similar article, as shown and described.

DESCRIPTION

FIG. 1 is a left (outer) side elevational view of a furniture arm frame or similar article showing my new design;

FIG. 2 is a top plan view thereof; and

FIG. 3 is a front elevational view; the rear elevational view being a mirror image thereof.

The side of the furniture arm frame not shown in FIG. 1 is conventional in appearance.
